UNITED STATES PATENT OFFICE.

LEONARD VAN PUTTEN, OF HOLLAND, MICHIGAN.

DESIGN FOR A LAP LUNCH-BOARD.

No. 39,490.

Specification for Design.

Patented Sept. 1, 1908.

Application filed June 2, 1908. Serial No. 436,304. Term of patent 14 years.

To all whom it may concern:

Be it known that I, LEONARD VAN PUTTEN, a citizen of the United States, residing at Holland, in the county of Ottawa and State of Michigan, have invented a new, original, and ornamental Design for a Lap Lunch-Board, of which the following is a specification, reference being had to the accompanying drawing, forming a part thereof.

The figure is a perspective view of a lap lunch board, illustrating my new design.

I claim:

The ornamental design for a lap lunch board, as shown.

LEONARD VAN PUTTEN.

Witnesses:

TONY MESSETINK,
D. J. TE ROLLER.
